his ATTORNEY.

UNITED STATES PATENT OFFICE

ALBERT VUILLEUMIER, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT

GRINDING MACHINE AND INTERCHANGER THEREFOR

Application filed June 27, 1922. Serial No. 571,285.

This invention relates to machines for grinding antifriction members, especially balls such as are used in antifriction bearings of the ball type, and has more particular relation to means for interchanging the balls during the grinding operation. Machines to which the invention is more particularly applicable comprise a pair of opposed discs between which the roughly formed antifriction members are ground. One of the discs is of suitable abrasive material, while the other disc is of steel or the like and is provided with a series of circular grooves concentric with the center of the disc and of successively increasing diameters, these grooves being for guiding and controlling the balls during the grinding operation. To secure proper grinding in machines of this character it is advisable not only that the balls, during the grinding, be moved from one groove to another but also that the positions of the balls be changed with respect to each other. I have devised a means for effecting this desirable shifting about or interchanging of the balls in a highly efficient and satisfactory manner.

One object of the invention is to provide a shaping, more particularly a grinding, machine in which the articles operated upon, as antifriction members, are efficiently and frequently shifted about or interchanged with respect to the guiding means, or grooves, and with respect to each other, during the shaping.

Another object is to provide an improved mixer or interchanger for changing the positions of the articles with respect to the guiding means and with respect to each other during the shaping.

To these ends and also to improve generally upon devices of the character indicated my invention consists in the various matters hereinafter described and claimed.

Without restricting the invention thereto I describe it with more particular reference to the embodiments thereof illustrated in the accompanying drawings. In these drawings:—

Figure 1 is a side elevation of the discs of a grinding machine, together with certain

of the immediately adjacent parts, with an antifriction member interchanger constructed in accordance with the invention combined therewith;

Figure 2 is a view comprising a section taken substantially on the line 2—2 of Figure 1 to show the interior construction of the interchanger, and the view also showing a portion of the guide-disc carrier and, in dotted lines, the grooves in the face of the guide disc;

Figure 3 is an enlarged section substantially on the line 3—3 of Fig. 1 (and Fig. 5) and showing the stripper-finger plate prior to the forming of the stripper-fingers;

Figure 4 is a view similar to Fig. 3 but showing the stripper-plate after the formation of the fingers;

Figure 5 is a view generally similar to Fig. 1 but showing a somewhat modified form of interchanger, and

Figure 6 is a fragmental view of the guide disc and the directing member for directing the antifriction members into the grooves after the members have had their positions changed by the interchanger.

Referring now to the drawings, and for the present more particularly to Figs. 1 to 4 and 6, the illustrated structure comprises a fixed guide disc 1, of steel or other suitable material, provided with guide grooves 2 for the balls, and carried by a carrier 3, and an opposed mating disc 4 of suitable abrasive material. As will be understood by those skilled in the art, the discs are, in use, suitably mounted upon any desired frame (not shown), proper means for driving the abrasive-disc-carrying shaft 5 thereby to rotate the abrasive disc 4, being provided, and the disc 1 being so mounted as to be urged towards the disc 4, as for example, by the expanding spring 6. The interchanger, to which the invention more particularly relates, is indicated in general at 7. As shown, the disc 1 is provided with a substantially rectangular opening 8 extending substantially radially thereacross and interrupting the grooves 2, and the carrier 3 is provided with a corresponding opening 9. The interchanger of the present invention is mounted at said

openings and with respect to the disc 1 in position to receive the balls from the downwardly facing open ends 2^a of the interrupted grooves 2, and to return them to the grooves 5 by supplying them to the upwardly facing open ends 2^b of the interrupted grooves, after proper mixing and interchanging.

As here shown, the interchanger 7 comprises in general an open-topped receptacle-like body having one end open as indicated at 10 (Fig. 2) and having a downwardly sloping partition 11 bridging the body and extending, longitudinally of the body from the open end thereof (which end is in immediate communication with the face of the disc 1, as indicated at 12) well toward the rear wall thereof as indicated at 13. The substantially flat bottom 14 of the receptacle has an inclination opposite to that of the partition 11 and communicates with the face of the disc 1 as indicated at 15.

It is to be particularly noted that whereas the edge 16 of the partition 11 is straight, as is desirable in order that it may properly mate 25 with the opening 8 in the disc 1, the partition is of concave and chute-like configuration substantially throughout its length. This provides that as the balls pass from the grooves 2 to the upper straight edge of the 30 partition, they tend to form in successive transverse rows and, moving down towards the concave delivery edge of the partition, are compelled by the transverse inclination to converge and pile up at the center. As the 35 balls drop from the end 13 of the partition they are spread out again by the flat inclined bottom 14 of the receptacle. Thus, a very efficient mixing of the balls is secured.

To insure that the balls departing from 40 the downwardly facing open ends 2^a shall be caught upon the edge 16 of the partition 11, the said edge extends well beyond the plane of the bottoms of the grooves 2, and preferably, as indicated in Fig. 3 at 18, the edge 16 projects forwardly from the face of the disc 1 substantially across the space between the disc 1 and the disc 4. Furthermore, the edge 16 is provided with stripper devices or fingers 19 (Fig. 4) which project into the 45 grooves 20 in the face of the abrasive disc 4 thus to insure the dislodging of the balls from the grooves 20.

The fingers 19 may be provided at the edge 50 16 in any desired manner. As here indicated the partition 11 embodies, attached to the body thereof, as by the screws 21, a plate 22 which presents the said fingers. As will be understood, these fingers may be formed in the edge of the plate 22 in any suitable manner; but as illustrating one convenient method of forming the fingers reference is made to Figs. 3 and 4. As illustrated in Fig. 3, the abrasive disc 4 is initially without grooves 20, the grooves being formed by the balls themselves during the grinding; correspondingly

the edge of the plate 22 is initially without fingers. As the grinding proceeds the balls form the grooves 20 and, as the spring 6 (Fig. 1) forces the disc 1 towards the disc 4 the edge of the plate 22 is ground into finger-presenting form by the disc 4. Of course, in cases where it is desired to use an abrasive disc initially formed with grooves, as 20, the plate 22 may be correspondingly initially formed with fingers, as 19, in any suitable machine, 70 the exact method of forming the fingers, and whether the fingers are provided upon the plate 22 before or after its installation in the grinder, not being of the essence of the invention. 75

In order that the balls departing from the bottom 14 may readily pass into the receiving ends 2^b of the interrupted grooves in the disc 1, (and into the grooves 20 of the disc 4) I preferably provide a directing plate 23 80 (Figs. 1, 2 and 6) which plate is provided (Fig. 6) on its forward edge 24 with straight grooves 25, lying substantially tangent to the grooves 2, and is formed with a portion 26 inclined backwardly and mating with the bottom 14. With this construction the balls, as they pass from the edge of the bottom 14, are suitably directed into the grooves of the discs despite the fact that such grooves are 85 arcs.

The interchanger 7 may be mounted with the disc 1 in any suitable manner. As here shown it is carried upon a bracket 27 adjustably mounted for vertical (in Fig. 1) movement relative to the carrier 3, and is adjustably connected with the bracket for movement toward and from the carrier and disc 1, as by bolts 28 in T-slots 29, said bolts also serving to adjustably hold the directing plate 23 in position, the bolts passing through slots 90 23^a in the plate. In order that the balls may be conveniently removed from the receptacle the bottom 14 of the same may, as shown, be provided with a discharge-slot-and-closing-slide 30, with the slide removably carried in 95 slots as 31 in the webs as 32 at each end of the discharge slot.

Referring now to Fig. 5 the modified interchanger there shown comprises a receptacle 33 substantially like the receptacle 7, except that its rear wall and a portion of its bottom are omitted, combined with a rotating drum 34. The drum is provided on its interior with a continuous upstanding flange 35 arranged in conveyor form as indicated. As the drum is rotated the balls discharge from the partition 36, and falling between the convolutions of the flange, are thoroughly mixed and ultimately discharged on to the bottom 37 of the receptacle, from which they pass into the open ends 2^b of the interrupted grooves of the disc 1 as previously described. The end of the bottom 37 immediately adjacent the drum is curved upward at each side 100 about the lower portion of the drum as indicated. 105

cated at 38 thus to give said end a somewhat trough-like form and close the space that would otherwise exist between the curved drum and the flat bottom 37.

5 While, for exactness and definiteness of description, I have described the invention as embodied in a grinder and interchanger for antifriction members it will be understood that the invention is not restricted to devices 10 for the production of antifriction members, nor is it restricted to the production of anti-friction members of ball-like character.

I claim:

1. In apparatus of the character described, 15 a rotary grinding member having article receiving grooves, in combination with an interchanger for removing the articles from the grooves and returning them to the grooves in a different order, said interchanger comprising a receptacle having a partition flat at one end and concave at the other to remove the articles from the grooves and cause them to converge and pile up, the bottom of the receptacle being flat and arranged 20 to receive the articles from the partition and spread them out before returning them to the grooves; substantially as described.

2. In apparatus of the character described, 25 a grinding member having article receiving grooves, in combination with an interchanger for removing the articles from the grooves and returning them to the grooves in a different order, said interchanger comprising 30 a receptacle having a partition extending entirely across it and spaced from the bottom of the receptacle, said partition and said bottom being oppositely inclined longitudinally of the receptacle and said partition being of 35 less length than the receptacle to provide a passage between the end of the partition and the end of the receptacle, the partition sloping downwardly towards said passage and having a straight receiving end to receive 40 articles from all of the grooves, the discharge end of the partition being concave upwardly to cause the articles to converge at the middle of the concavity, and the bottom of the receptacle being flat and sloping downwardly 45 from the passage to the grooves to spread out the articles; substantially as described.

50 In testimony whereof I hereunto affix my signature.

ALBERT VUILLEUMIER.
